SEWER CLEANER

Andrew E. Kelpsh, Miami Beach, Fla.

Application August 30, 1939, Serial No. 292,737

2 Claims. (Cl. 15—104.30)

This invention relates to a sewer cleaning apparatus and has special reference to a self-propelled apparatus of this character.

One important object of the invention is to provide an apparatus of this class wherein are combined mechanical and hydraulic means for cleaning a sewer in advance of the instrumentality employed.

A second object of the invention is to provide a mechanical sewer cleaner combined with a hydraulic cleaner wherein, whenever the mechanical cleaner becomes clogged by accumulation in front thereof the hydraulic cleaner may be brought into play so that a clear path is established for the mechanical cleaner.

With the above and other objects in view, as will be hereinafter apparent, the invention consists in general of certain novel details of construction and combinations of parts hereinafter fully described, illustrated in the accompanying drawings and pointed out in the appended claims.

In the accompanying drawings, like characters of reference indicate like parts in the several views, and—

Figure 1 shows a vertical longitudinal section through a sewer with the invention applied thereto under one condition of application.

Figure 2 is a view similar to Figure 1 but showing a second arrangement of the invention.

Figure 3 is an enlarged side elevation of the invention as applied to the sewer of Figure 1.

Figure 4 is a plan view of the arrangement as shown in Figure 3.

Figure 5 is an elevation on the line 5—5 of Figure 3.

Figure 6 is a section on the line 6—6 of Figure 4.

In the drawings herein illustrating the embodiment and use of the invention there is shown in Figures 1 and 2, a sewer section 10 having manholes 11 and 12 at opposite ends of the section 10, the flow being from the manhole structure 11 towards the structure 12 as indicated by the arrows 13.

The cleanout instrumentality forming the present invention includes a piston or disk 14 adapted to fit closely within the sewer section 10. This piston or disk while herein shown as including a lower part 15 and an upper part 16 which are connected above the median central lines of such parts by hinges 17 so that the upper part 16 can be folded back with respect to the lower part 15 may be formed of a plurality of sections similarly connected together.

The lower part 16 is supported on a carriage

consisting of a pair of parallel members 17' between which is journaled a forward supporting wheel 18. Journaled in the members 17' is an axle 19 whereon is supported wheels 20.

The upper section 16 is connected by links 21 with a slide member 22 normally held forward by springs 23. The slide member 22 is guided by yokes 25 and has a shaft 26 engaging beneath said yokes. The slide 22 is connected to a pull cable as at 28 and this pull cable 29 passes under a pulley 30 secured to the rear of the members 17' and extends rearwardly under a pulley 31 carried by a prop 32 disposed in the manhole 11 as shown in Figures 1 and 2 to the exterior of the sewer where suitable operating means (not shown) are connected thereto.

It is to be observed that the parts 15 and 16 are connected by a rubber sheet 33 severed laterally on a line with the hinge joint as indicated by the letter C and are cut away as at 34 to enable folding or angular disposition thereof with respect to each other, said rubber sheet having its center cut out as indicated by the letter D in the drawings.

In order to hold the device down and prevent side lashing of the same within the sewer a suitable weight 34 is secured to the members 17'.

A forwardly extending fin 35 is secured to the part 15 in order to facilitate the forward movement of the device over uneven points or any fixed obstructions.

In operation, the device is set up as in Figure 1 and by hydraulic pressure therebehind will force the sludge forwardly as at S. Eventually this will result in jamming the member 14 so that it cannot push the sludge S in front of it. Now, by turning the member 16 to open the passage the upper portions of the sludge are washed out and, upon closing the part 16 the cleaning head again advances.

There has thus been provided a simple and efficient device of the kind described and for the purpose specified.

What is claimed is:

1. In a sewer cleaner, a carriage including a frame and wheels supporting the frame, a piston including a lower segment fixed to the forward end of the frame and an upper segment hinged to the lower segment and foldable backwardly over the forward end of the frame, guide means carried by and extending longitudinally of said frame, a slide guided by said means, links connecting said slide and the upper part of said upper segment, springs connecting said slide and frame and urging said slide forwardly and

thereby to swing the upper segment into operative position, and means connected to said slide for retracting the latter against the action of said springs.

- 5 2. In a sewer cleaner, a carriage including a frame and wheels supporting the frame, a piston including a lower segment fixed to the forward end of the frame and an upper segment hinged to the lower segment and foldable backwardly
10 over the forward end of the frame, guide means carried by and extending longitudinally of said

frame, a slide guided by said means, links connecting said slide and the upper part of said upper segment, springs connecting said slide and frame and urging said slide forwardly and thereby to swing the upper segment into operative position, means connected to said slide for retracting the latter against the action of said springs, and traction means for the carriage connected to the last mentioned means.
